(57) CLAIM

I claim the ornamental design for a bathtub, as shown and described.

DESCRIPTION

FIG. 1 is a front, top, right side perspective view of a bathtub showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, bottom, right side perspective view thereof. Broken lines represent portions of the bathtub that form no part of the claimed design.
